(57) **CLAIM**

We claim the ornamental design for a covering for an architectural opening having a sheet with a pattern, as shown and described.

DESCRIPTION

FIG. 1 is an isometric view of a covering for an architectural opening having a sheet with a pattern; and,

FIG. 2 is an enlarged detail view of area 2 circumscribed within FIG. 1.

The broken lines showing portions of a covering for an architectural opening having a sheet with a pattern in FIG. 1 depict environment and form no part of the claimed design. The dot-dash-dot broken lines surrounding FIG. 2 depict the boundaries of the detail and form no part thereof.
